WATER COOLER

Howard E. Blood and Orrin A. Brandel, Detroit,
Mich., assignors to Norge Corporation, Detroit,
Mich., a corporation of Michigan

Application January 9, 1931. Serial No. 507,564

4 Claims. (Cl. 62—116)

This invention relates to an improved bottled water cooling arrangement associated with domestic refrigerators of the mechanical or absorption type.

- 5 It is an object of this invention to provide an improved water cooling arrangement in connection with domestic refrigerators of the electric or gas operated type incorporating a freezer or evaporator unit in the refrigerated compartment. It
 10 is an advantage to provide a water cooler in combination therewith if the cooler element does not usurp too much of the refrigerator space, as by providing a pre-cooled supply of drinking water it becomes unnecessary to overwork the ice cube
 15 trays of the freezer or evaporator unit, with a consequent waste and inconvenience and delay surrounding the direct ice cooling of a tepid drinking water supply, especially when only a small quantity of water is required.
 20 It is also an object of this invention to provide an improved drinking water fount or supply applicable to domestic refrigerators of the type mentioned, which in its principal form is adapted to be built into the refrigerator while being fed
 25 from an automatic fount formed to receive the usual five gallon bottles in which drinking water is customarily retailed. In a modified form, the structure of this invention is adapted for use in existing refrigerators where it is not practical to
 30 use the automatic fount and bottle supply.

It is another object of this invention to provide a water cooling reservoir insertible beneath the freezer and evaporator unit and above the usual drip pan, the reservoir being so formed that
 35 condensation on or drippage from the freezer will not lodge on the reservoir.

It is still another object of this invention to provide a readily removable cooling water reservoir to facilitate the maintenance thereof in a
 40 sanitary condition.

Other and further important objects of this invention will be apparent from the disclosures in the specification and the accompanying drawings.

This invention (in a preferred form) is illustrated in the drawings and hereinafter more fully described.

On the drawings:

Fig. 1 is a front elevation of a refrigerator cabinet, with the door omitted, to show the application of one embodiment of this invention thereto.

Fig. 2 is an enlarged cross-section of the cooling reservoir in a plane parallel to Fig. 1.

Fig. 3 is a fragmentary enlarged section on the

line III—III of Fig. 1 with parts in elevation, showing the draw-off cock.

Fig. 4 is a fragmentary section on the line IV—IV of Fig. 1, showing the slip joint for the supply pipe.

Fig. 5 is a front elevation of a modified embodiment of this invention wherein the supply fount is omitted.

As shown on the drawings:

The cabinet chosen for illustrative purposes comprises a refrigerated compartment 10 formed in a box 11, the top 12 of which is specially formed for the purposes of this invention. It is usual in such structures to at least form the compartment with a porcelain or enameled steel lining and in the embodiment shown the outer casing 13 is similarly formed although, such details form no part of this invention. Mention is made of them merely because of the modified form of reservoir supplied for use in existing refrigerators, since it is difficult to cut openings in the enameled steel casing of a completed refrigerator.

The compartment 10 contains a freezer or evaporator unit 14 as well as suitable shelving 15, one of which carries provision for the suspension of a drip pan 16 beneath the freezer unit 14.

In both forms of the invention, a water cooling reservoir 17 is positioned on a shelf above the drip pan and beneath the freezer unit. While the reservoir could be located elsewhere the specified location is preferable, since this is the coldest place in the refrigerator, where the air circulation is ordinarily partially obstructed by the drip pan. The reservoir top 18 is preferably slightly rounded to permit drainage of water into the drip pan when defrosting the freezer unit. The reservoir may preferably be made of glass in order that its cleanliness may be evident and in the second form to also show the amount of water present; but a metal or porcelain finish is of compensating value because of durability, especially in the built-in form.

The built-in type of cooler reservoir shown in Fig. 1 et seq. is kept supplied with water from a fount preferably applied to the refrigerator top. As shown the fount comprises a water seal chamber 19 above which is a bottle supporting ring 20 through which the mouth 21 of an inverted water bottle 22 projects. As is well known, this type of fount is self-feeding in that the bottle feeds water until the level thereof in the chamber 19 rises to cover the mouth of the bottle. When the water level drops sufficiently to admit air to the bottle the feed recommences.

until the bottle is again air bound by a rise in the water level. The water seal chamber 19 is formed as a dish 23, the rim of which carries sealing material 24 fitting into a raised rim 25 about the opening in the refrigerator top to prevent an accidental overflow of water from reaching and damaging the dry insulating material between the compartment lining and the outer casing.

10 The chamber 19 is connected to an inlet nipple 26 on the reservoir 17 by means of a pipe 27 disposed close to the side of the freezer and, preferably, mounted in slip joints for ease in disconnecting the reservoir. The upper joint, as 15 shown in Fig. 4 comprises a flanged sleeve 28 surrounding the pipe and compressed thereagainst by a nut 29. The lower joint shown in Fig. 2 utilizes packing 30 clamped by a nut 31 screwed onto the nipple 26.

20 An outlet nipple 32 is provided on the lower side of the reservoir adjacent the side wall of the compartment, to receive a short length of tubing 33 clamped in place by packing 34 and a nut 35, the tubing leading to a union 36 from 25 which tubing 37 leads through the compartment lining and thence in the walls of the refrigerator to a push type of faucet 38 which is preferably located in the sill below the compartment in order not to be subject to damage should the 30 door be swung back. This arrangement conserves the cold within the refrigerator as it is not necessary to open the door to draw off a supply of drinking water.

The self contained or removable type of reservoir 39 shown in Fig. 5 is intended to be supplied for existing refrigerators, as it is impractical to cut holes in the enameled steel of completed cabinets for the built-in type previously described. In this form of the invention an oval or round 40 opening 40 is provided towards the front of the reservoir for filling and cleaning purposes. A rim 41 as well as a closure 42 are applied to the opening to prevent undesirable contamination of the contents. A discharge outlet 43 is also provided for a faucet 44. In this case the cabinet door would have to be opened for the filling and removal of water.

In the use of the built-in form of this invention the inverted supply bottle 22 maintains the 50 water supply in the chamber 19 level with the extremity of the mouth of the bottle so that the chamber 19 and connecting pipe have a substantial pre-cooling effect before the water reaches the reservoir. Since the draw-off is from adjacent the bottom of the reservoir only the cold- 55 est water, which has settled to the bottom on cooling, is drawn off, so that a relatively large supply of cooled water is available. Further, the location of the reservoir beneath the freezer 60 unit assures a very rapid cooling of the water, so that heavy demands can be made on the water supply without obtaining tepid water.

We are aware that many changes may be

made, and numerous details of construction may be varied through a wide range without departing from the principles of this invention, and we therefore do not purpose limiting the patent granted hereon, otherwise than necessitated by 80 the prior art.

We claim as our invention:

1. In combination with a refrigerator and a 85 freezer unit mounted in the refrigerated compartment thereof, a water cooling reservoir in said compartment positioned beneath said freezer unit, a water bottle fount positioned outside the refrigerator for feeding water to said cooling reservoir, conduit means connecting said fount and said reservoir, said means including readily 90 detachable connections for facilitating the removal and cleaning of said reservoir, a draw-off connection from said reservoir, and a faucet connected thereto and mounted on the outside of 95 said refrigerator.

2. In combination with a refrigerator and a 100 freezer unit mounted in the refrigerated compartment thereof, a water cooling reservoir in said compartment positioned beneath said freezer unit, said reservoir having a rounded top to facilitate drainage of water when defrosting the 105 freezer unit, a water bottle fount positioned outside the refrigerator for feeding water to said cooling reservoir, conduit means connecting said fount and said reservoir, said means including 110 readily detachable connections for facilitating the removal and cleaning of said reservoir, a draw-off connection from said reservoir, and a faucet connected thereto and mounted on the outside of 115 said refrigerator.

3. In combination with a refrigerator and a 120 freezer unit mounted in the refrigerated compartment thereof, a water cooling reservoir in said compartment positioned beneath said freezer unit, a water bottle fount positioned outside 125 the refrigerator for feeding water to said cooling reservoir, said fount including means preventing overflow of water into the refrigerator casing, conduit means connecting said fount and said reservoir, said means including readily detachable connections for facilitating the removal and cleaning of said reservoir, a draw-off connection from said reservoir, and a faucet connected thereto and mounted on the outside of 130 said refrigerator.

4. In combination with a refrigerator and a 135 freezer unit mounted in the refrigerated compartment thereof, a water cooling reservoir in said compartment positioned beneath said freezer unit, a water bottle fount positioned outside 140 the refrigerator for feeding water to said cooling reservoir, conduit means connecting said fount and said reservoir, said means including readily detachable connections for facilitating the removal and cleaning of said reservoir.
